UNITED STATES PATENT OFFICE.

CHARLES S. HENRY, 2d, AND THOMAS WELLS, OF NEW YORK, N. Y.

GOLF-CLUB.

1,201,728.

Specification of Letters Patent. Patented Oct. 17, 1916.

Application filed December 21, 1915. Serial No. 68,056.

To all whom it may concern:

Be it known that we, CHARLES S. HENRY, 2d, and THOMAS WELLS, citizens of the United States, residing at New York city, in 5 the county of New York and State of New York, have invented certain new and useful Improvements in Golf-Clubs, of which the following is a full, clear, and exact description, such as will enable others skilled 10 in the art to which it appertains to make and use the same.

This invention relates to golf clubs and more particularly to that form of club known as a putter since it is in connection 15 with such a club that the invention may be used to especial advantage.

One of the objects of the invention is to produce a golf club so constructed as to permit its grip or handle to be adjusted 20 to any desired degree, thereby contributing to greater ease and accuracy of manipulation.

A further object is to produce a club possessing the above characteristics in which 25 while only a simple bending operation is necessary to render the grip of the club suitable to the individual player, the grip possesses sufficient rigidity to withstand the usage of play without bending.

30 Other features of the invention will be in part obvious and in part pointed out hereinafter.

The invention consists in the features of construction, combination of elements and 35 arrangement of parts which will be exemplified in the construction hereinafter set forth, and the scope of the application of which will be indicated in the following claims.

40 In the drawing, in which is shown one of the embodiments of the several features of our invention, Figure 1 is a front elevation of a golf club showing the hands in position on the grip. Fig. 2 is a similar view of the 45 club alone, and Fig. 3 is a view partly in section showing the details of construction of the grip.

50 Referring now to the drawing, in which similar reference characters denote similar parts throughout the several views thereof, 2 is the head of a golf club which in the present instance is shown as a putter. To the shank 3 of the head is attached a shaft 4 having at its other end a grip 5 constructed in accordance with the present invention. As shown most clearly in Fig. 3 the grip

5 comprises a metal core 6 preferably formed of seamless, steel tubing, thus providing at one end a socket 7 to fit over the upper end of the shaft 4 to which it is attached in any 60 convenient manner. At its outer end the core also forms a socket 8 into which may be placed a cap 9 to give a finished appearance to the club. Between the sockets the core is formed with a constricted portion 65 10 which should be of sufficient rigidity to retain the socket portions in normally fixed relationship to each other while at the same time permitting their relationship to be altered at the will of the user by a simple bending operation. The constricted portion 10 is preferably formed of diminishing thickness in the direction shown, but of substantially the same width as the remaining portions of the core in a direction at 70 right angles thereto. This arrangement permits bending of the grip 5 in the plane in which the head 2 lies, but offers considerable resistance to bending out of this plane, thus preventing any tendency to bend during 75 use of the club.

Rubber slugs 11 are provided which fit into the indentations about the constricted portion 10, in order to provide a grip of uniform diameter throughout. The slugs 85 have gores cut therein as at 12 to facilitate the bending of the rubber as the angle of the grip is changed, as shown in Fig. 2. The entire grip may be bound with leather, rubber, or other material as is customary in 90 devices of this character.

It will be seen from the above described construction that a golf club is provided in which the grip or handle thereof may be readily adjusted to meet the needs of the 95 user. The grip has been shown as normally bent at an angle of approximately 45 degrees so as to give the greatest bending facility not only back to the perpendicular but to an angle of 90 degrees according to 100 the requirements of the individual player. It will be understood, however, that the grip may be manufactured with its two sockets in a straight line to be later bent to any desired degree by a user. It will therefore be 105 seen that there is provided a device well adapted to accomplish, among others, all of the ends and objects hereinbefore set forth in an exceedingly simple and efficient manner, and that structurally considered the 110 device is of the greatest possible simplicity, which the nature thereof will permit, and

is well adapted to be made at a minimum of cost and to be readily assembled into a neat and compact arrangement for accomplishing the purposes intended.

5 As many changes could be made in the above construction and many apparently widely different embodiments of this invention could be made without departing from the scope thereof, it is intended that all matter contained in the above description or 10 shown in the accompanying drawings shall be interpreted as illustrative and not in a limiting sense.

Having described our invention, what we 15 claim as new and desire to secure by Letters Patent is:

1. A device of the character described comprising, in combination, a head, a shaft secured to said head, and a grip secured to 20 said shaft, said grip comprising a plurality of tubular members, a constricted pliable portion therebetween, filling members surrounding said constricted portion and a binder around said tubular members and 25 said filling members.

2. A device of the character described comprising, in combination, a head, a shaft secured to said head, and a grip secured to 30 said shaft, said grip being constructed to be bendable at a point intermediate its length.

3. A device of the character described comprising, in combination, a head, a shaft secured to said head, a grip secured to said 35 shaft, and having a constricted portion inter-

mediate its length, whereby it may be bent at any angle to the line of said shaft.

4. A device of the character described comprising, in combination, a head, and a handle associated with said head, the upper 40 part of said handle adjacent the end thereof being adapted to be bent at will at an angle to the line of the handle.

5. A golf club provided with a pliable handle. 45

6. A golf club provided with a head and a non-resilient handle pliable in a direction parallel to said head and relatively rigid in a direction at right angles to said head.

7. A golf club having a shaft with a head 50 on one end and a handle on the other end angularly adjustable with respect to said shaft in a direction parallel to said head.

8. A handle for a golf club comprising a plurality of tubular members, a constricted portion between said members so formed as to permit relatively easy bending of said handle in one plane, while preventing bending of said handle in other planes, and filling members adjacent said constricted portion for maintaining the diameter of said handle relatively constant throughout its 55 length.

In testimony whereof we affix our signatures in the presence of two witnesses.

CHARLES S. HENRY, 2ND.
THOMAS WELLS.
